CLAIM

The ornamental design for a television apparatus, as shown and described.

DESCRIPTION

1. Television apparatus

1.1 : Perspective

1.2 : Rear perspective

1.3 : Front

1.4 : Back

1.5 : Left

1.6 : Right

1.7 : Top

1.8 : Bottom

1.9 : Enlarged

1.10 : Enlarged

The broken lines depict portions of the article that form no part of the claimed design; the dot-dashed lines indicate
